DESIGN.

W. J. KEEP & C. WIPFLER.

HEATING STOVE.

No. 18,190.

Patented Mar. 20, 1888.

UNITED STATES PATENT OFFICE.

WILLIAM J. KEEP AND CHARLES WIPFLER, OF DETROIT, MICHIGAN,
ASSIGNORS TO THE MICHIGAN STOVE COMPANY, OF SAME PLACE.

DESIGN FOR A HEATING-STOVE.

SPECIFICATION forming part of Design No. 18,190, dated March 20, 1888.

Application filed June 9, 1887. Serial No. 240,830. Term of patent 7 years.

To all whom it may concern:

Be it known that we, WILLIAM J. KEEP and CHARLES WIPFLER, citizens of the United States, residing at Detroit, in the county of Wayne and State of Michigan, have invented 5 a certain new and original Design for Stoves, of which the following is a specification, reference being had therein to the accompanying drawing.

10 This design is particularly adapted to res-
ervoir heating-stoves.

On referring to the accompanying photo-
graph it will be seen that the most salient fea-
ture of this design is the peculiar shape of the
15 upper portion, the front and sides of which
are substantially alike.

For convenience in describing the design
we shall first name and number the different
20 sections of the stove as follows: the statuette,
1; the cover, 2; the overhanging top section,
3; the mica cover, 4; the upper mica-section,
5; the lower mica-section, 6; the ash-pit, 7;
the lower flue-section, 8; the leg-base, 9; the
25 buttresses, 17; the diverging corner ornaments
or wings, 10, and the oven 11.

As before stated, the main novelty of this
design consists in the peculiar overhanging or
recessed top, and the features that render this
30 particularly novel are the recesses and the in-
turned mica cover.

Referring now to the details of our design,
it will be seen on referring to the accompa-
nying photograph that on the top of the stove is
a statuette representing a Roman soldier pro-
35 vided with helmet, shield, and breastplate,
and carrying a drawn sword in his right hand.
The statuette stands on a base, A, around
which are hung garlands, and the base stands
on the cover 2, the upper portion of which is
40 convex, but terminates in a square base with
plain sides and a figured edge. The top sec-
tion, 3, is of peculiar shape, being substan-
tially round on top, descending in curved
lines at the corners, as at B, and is ornamented
45 with scrolls of various forms. On the sides
the cover has concave or shell-shaped recesses,
under which are the mica-cover frames 4, con-
sisting of curved rims connected together by
bars radiating on lines drawn from a point
50 near the center of the bottom line of the shell-

shaped recesses. Immediately below the mica
cover is the upper mica-section, 5, formed
mainly of door-frames made up of irregularly-
arranged bars, and below this again is the lower
mica-section, 6, also made up of door-frames 55
having irregularly-set bars, but arranged some-
what differently from those in the upper mica-
section, 5. Below this section is the ash-pit 7,
consisting (so far as appears in the illustration)
of the top C, ornamented by a series of scrolls 60
in front and short ribs or flutes at the side,
the side plate, c, ornamented by scrolls, and
the ash-pit door c', which is also ornamented
by scroll-work, and shows an oblong opening,
parallel with which is a series of short lines 65
and a short projecting bar reaching from the
center of the opening to the series of short
lines. Below the series of short lines there is
space for fancifully-shaped lettering. At each
70 side of the ash-pit is a rail, D, having an ob-
liquely-set rosette, d.

At 8 is shown the lower flue-section, which
is ornamented with the scroll-work shown.
Below the flue-section 8 is the leg-base 9, or-
namented with a series of scrolls beginning 75
near each corner and running toward the
center, with the end turned in opposite direc-
tions. Between the opposite ends of each
scroll is a series of lines arranged in pairs,
starting from near one end of the scroll, the 80
pairs of lines diverging as they run toward the
top of the base. Between each two pairs of
lines are beads of gradually-increasing size as
they run from the starting-point below to-
ward the top of the base. The legs are each 85
ornamented with a three-pointed leaf and ter-
minate in a toe simulating a grotesque or non-
descript head. Between the front legs is a
downwardly-projecting ventilating flue; but
this we may sometimes omit. At each of the 90
front corners is a diverging corner ornament
or wing, the upper part simulating a dragon
or other nondescript winged animal, 12, the
lower part of which forms a scroll. A rosette,
13, which is connected by scroll-work with 95
the lower part of the winged animal, is shown
at the bottom of the buttress. The oven rests
on a bracket, 14, at the back of the stove.
It is ornamented by scroll-work. The door
15 of the oven has a medallion in its center, 100

on which is a shield surrounded by scroll-work. The surface of the door is also ornamented with scrolls made up of finer lines. The top of the oven is surrounded with a molding, 16, ornamented with scrolls.

At each corner of the stove is a buttress, 17, running from the top of the upper mica-sections to the bottom of the lower mica-sections. The two front buttresses are behind the wings 10.

What we claim as new is—

1. A design for a stove, comprising the figure 1, the cover 2, the overhanging top 3, the cover 4, the upper mica-section, 5, the lower mica-section, 6, the ash-pit 7, the lower flue-section, 8, the leg-base 9, the wings 10, and the oven 11, all having the shape shown.

2. In a design for a stove, an overhanging top, 3, having an inturned concave recess in front above the cover, as shown.

3. In a design for a stove, the substantially cylindrical fire-pot section, comprising the three mica-sections, the lower one flaring, the upper one of sector shape, and the intermediate one substantially straight, as shown.

4. In a design for a stove, the rail ornamented at its ends with rosettes arranged at an oblique angle to the length of the rail, as shown.

5. In a design for a stove, the body having side and front doors and extended diverging parallel-sided ornaments between them and running from top to bottom of the doors, as shown.

6. In a design for a stove, the leg-base ornamented by scrolls beginning at each corner and running toward the center in the shape of a fan, as shown.

7. In a design for a stove, a leg ornamented by a pointed branched upwardly-extending leaf in the center of its body and a nondescript head below the same, as shown.

8. In a design for a stove, a parallel-sided projecting wing ornamented with a nondescript winged animal, as shown.

9. In a design for a stove, the oven-door 15, having its surface ornamented with fine scroll-work and a projecting medallion ornamented by a shield, which shield is surrounded by scroll-work.

In testimony whereof we affix our signatures, in presence of two witnesses, this 6th day of June, 1887.

WILLIAM J. KEEP.
CHARLES WIPFLER.

Witnesses:

JOHN M. DWYER,
ISAAC S. FILER.
